(57) **CLAIM**

The ornamental design for a children's riding toy, as shown and described.

DESCRIPTION

FIG. 1 is a perspective view taken from the front, right side, and top side of a scooter of the children's riding toy of the present invention, shown separately for the clarity of illustration.

FIG. 2 is a front elevation view of the scooter of FIG. 1.

FIG. 3 is rear elevation view of the scooter of FIG. 1.

FIG. 4 is a top plan view of the scooter of FIG. 1.

FIG. 5 is a right side elevation view of the scooter of FIG. 1.

FIG. 6 is a left side elevation view of the scooter of FIG. 1. FIG. 7 is a perspective view taken from the front, right side, and top side of a removable seat of the children's riding toy of the present invention, shown separately for the clarity of illustration.

FIG. 8 is a front elevation view of the seat of FIG. 7.

FIG. 9 is rear elevation view of the seat of FIG. 7.

FIG. 10 is a top plan view of the seat of FIG. 7.

FIG. 11 is a perspective view taken from the front, right side, and bottom side of the seat of FIG. 7.

FIG. 12 is a right side elevation view of the seat of FIG. 7.

FIG. 13 is a left side elevation view of the seat of FIG. 7.

FIG. 14 is a perspective view of a first configuration of the children's riding toy of the present invention including the scooter of FIG. 1 with the handlebars in a lowered position and with the seat of FIG. 7 attached as a seat; and, FIG. 15 is a perspective view of a second configuration of the children's riding toy of the present invention including the scooter of FIG. 1 with the handlebars reversed and in a lowered position and with the seat of FIG. 7 attached as a bucket.

Elements drawn in dash-dash lines are included for illustrating portions of the children's riding toy that form no part of the claimed design.

1 Claim, 15 Drawing Sheets
